(57) CLAIM

The ornamental design for a wearable audio component, as shown and described.

DESCRIPTION

FIG. 1 is a perspective view of a wearable audio component showing the new design;

FIG. 2 is another perspective view thereof;

FIG. 3 is a front elevational view thereof;

FIG. 4 is a rear elevational view thereof;

FIG. 5 is a side elevational view of one side thereof;

FIG. 6 is a side elevational view of the opposite side thereof;

FIG. 7 is a top plan view thereof; and,

FIG. 8 is a bottom plan view thereof.

The broken lines and unshaded areas form no part of the claimed design. The contrasts in stippling and shade lines represent contrasts in appearance only and do not represent any particular material, texture, or finish.
